MACHINE AND METHOD FOR CLADDING PIPES AND THE LIKE

Victor E. Knapp, Roslyn, N. Y., and Otto F. Schmidt, Wilmington, Del., assignors to Knapp Mills Incorporated, Long Island City, N. Y., a corporation of New York

Application June 22, 1954, Serial No. 438,432

11 Claims. (Cl. 118—69)

The present invention relates to a method and apparatus for applying protective coatings to pipes, tubes and rods and more specifically to an improved and simplified system for attaining firmly bonded, uniform and homogeneous coatings of lead and other similar materials.

While many systems have been proposed for applying protective coatings to rods and tubes, they have involved relatively complicated and expensive procedures, not entirely satisfactory for general commercial application. Some of these processes, for instance, employed means for maintaining the coating material under pressure which necessitates the use of costly equipment including pumps, valving means and the like, while others involved quite complicated systems for moving the pipe or rod horizontally through a bath of the metal. Moreover, none of these prior processes provide effective and positive means for the effective release and removal of oxides and foreign particles that may become entrained in the bath nor precisely controlling the thickness, uniformity and homogeneity of the coating. Accordingly, one object of the invention is to provide apparatus that not only overcomes the disadvantages of prior structures but also provides means wherein the rods and tubes may be fed obliquely into a bath to successively subject a large area of the periphery thereof to the coating material. This procedure facilitates the removal of oxides and foreign matter from the surface of the articles being coated and at the same time protects the surface from further oxidation immediately prior to immersion in the bath. The release of this foreign matter on the surface of the bath generally facilitates its removal and prevents it from becoming entrained therein where it may embed itself in the clad and produce serious imperfections.

Another object of the invention resides in the provision of cladding apparatus wherein breaks of imperfections in the clad resulting from interruption in the operation and entrainment of foreign matter are effectively prevented and an improved clad firmly bonded, both mechanically and chemically, to the pipe is provided that is free of imperfections and distortions.

A further object of the invention is an improved method for cladding rods and tubes that will produce a sturdier and more uniform coat free from imperfections and at greatly increased speeds.

Still another object of the invention is the provision of rod and tube cladding means characterized by its simplicity, effectiveness and low maintenance and operating costs.

The above and other objects of the invention will become more apparent from the following description and accompanying drawings forming part of this application.

In the drawings:

Fig. 1 is a plan view of one embodiment of the invention for cladding rods, pipe and tubing;

Fig. 2 is a cross sectional view of Fig. 1 taken along the lines 2—2 thereof;

Fig. 3 is a cross sectional view of the coating bath along the lines 3—3 of Fig. 1;

2

Figs. 4 and 5 are cross sectional views of Fig. 2 taken along the lines 4—4 and 5—5 thereof;

Fig. 6 is an enlarged sectional view of the pipe guiding means at the terminal end of the cladding bath to illustrate more clearly the construction thereof; and

Fig. 7 is a cross sectional view of Fig. 6 taken along the lines 7—7 thereof.

Briefly, the illustrated embodiment of the apparatus comprises five basic sections, namely, the cladding bath 10 through which the rod or tube to be cladded is passed, a guide for controlling the thickness of the cladding applied to the pipe, means for solidifying the cladding, a plurality of pressure rollers completely encompassing the cladded pipe to remove all imperfections that may be in the clad and effect the desired homogeneity and, lastly, means for exerting a longitudinal force on the cladded pipe to pull it through the apparatus during the cladding operation.

More specifically, and with reference to the figures, 20 the cladding bath 10 has an elongated inner section in the form of a U-shaped trough formed integrally with a pair of spaced side walls 12. The left-hand or entry end of the trough 11 as observed in Fig. 2 is provided with an end wall 13 having an opening 14 through which the pipe 15 to be cladded is inserted. The opposite or 25 exit end of the trough 11 is provided with an end wall 16 having a guide 17 secured within an opening 18 therein through which the pipe leaves the bath 10. During the operation of this equipment, a molten cladding material 19 such as lead or the like is retained within the trough 11 which is tilted so that the surface of the molten material 19 lies below the bottom of the opening 14 and extends well above the top of the opening 18, in the wall 16, and the associated guide 17. To effect 30 this end the trough 11 is preferably made shallower at the entrance end than it is at the exit end and the entire trough, including the walls 12, may be tilted so that both the pipe 15 and the trough 11 slope downwardly from the entrance to the exit of the trough at substantially a uniform rate. While not shown in the drawings, suitable heating means for the trough 11 may be provided to maintain the material 19 in a molten state.

As the pipe 15 is moved through the molten bath 19 at an angle as shown in Fig. 2, successive sections of 45 the pipe enter the bath with the bottom side of the pipe advancing into the bath before corresponding points on the top side thereof. With this arrangement the coating is applied to the pipe at about a substantially horizontal elliptical path which enables more of the coating 50 to be applied at a given time and thus permits the coating operation to be carried out at increased speeds. Since the pipe 15 enters the surface of the bath 19, it may be thoroughly cleaned immediately prior to the application 55 of the coating by floating on the surface of the molten material 19 a suitable flux 20 such as zinc chloride and the like through which the pipe must pass before entering the actual coating material. The utilization of a flux in this manner results in the effective removal of 60 foreign matter including oxides from the pipe and protects the cleaned surface from further oxidation before application of the clad. In addition, the foreign matter thus released does not become entrained within the molten material but floats on the surface where it may be easily 65 removed. If desired, the pipe 15 may also be cleaned by conventional mechanical abrasive processes and, if desired, also coated with a suitable flux prior to entering the trough 11 for the coating operation in order to insure a more positive bond, especially in the cases where substantial quantities of oxide may have formed on the 70 surface of the pipe.

In order to insure accurate control of the thickness of the coating applied as the pipe or tubing 15 passes through

the molten material 19, a guide 17 is provided at the exit end of the bath. This guide is in the form of a tubular member 21 having a centrally disposed flange 22 extending outwardly therefrom, as shown in Fig. 6. This flange is secured tightly against the end wall 16 of the trough 11 by a collar 24 bolted against a circular flange 25 extending from and formed integrally with the wall 16. In order to prevent leakage of the molten material, a high temperature packing 23 such as asbestos is inserted between the flange 22 and the wall 16. The inside diameter of the tubular guide 21 determines the thickness of the coating that will form on the pipe 15 while it is within the bath 19. In order to insure a uniform thickness of the coating about the entire periphery of the pipe, a plurality of ribs 26 of relatively thin section are provided which ride on and center the pipe 15 within the tubular member 21. The ribs are disposed substantially wholly within the bath 10 so that the molten material will flow around the ribs as the pipe 15 passes therethrough to form a uniform and continuous coating completely about the pipe and without any evidence in the form of a longitudinal seam or groove evidencing the use of ribs.

As the pipe 15 with the cladding 15' leaves the guide 17, it passes through a water jacket assembly 28 accurately aligned with the guide tube 21 and surrounded by an outer jacket 29, as shown in Fig. 2. This outer jacket 29 is essentially cylindrical in shape and is provided with a flanged end part 31 secured to the end wall 16 of the bath 10 by means of a disc 32 interposed therebetween. This disc has a central opening 33 surrounding the flange 25 extending from the end wall 16 of the bath 10 and is fastened to the end wall 16 of the bath by bolts 34 and to the flange 31 by bolts 34' so that the bath 10 and the housing 29 provide a substantially unitary structure.

The cooling jacket 28 is cylindrical in shape and has an inner wall 35 immediately surrounding the pipe 15 and an outer wall 36 which is spaced from the inner wall to provide a circular channel 37 for the circulation of water. The inner and outer walls of this jacket are connected by a pair of end flanges 38 and 39 which completely seal channel 37. The flange 38 is bolted to a flange 40 that may be formed integrally with the right-hand end of the guide tube 21 as shown in Fig. 2 so that the cooling jacket 28 is accurately aligned with and in effect forms part of the guiding tube 21. To effectively align the cooling jacket and guiding tube with the entrance opening 14 in the bath 10, three bolts 41 are provided which are secured at intervals of 120 degrees to the flange 39 of the water jacket 28 and extend outwardly through the wall of the outer housing 29, as shown in Fig. 4. By the adjustment of the nuts 42 cooperating with these bolts 41, accurate and precise alignment of the cooling jacket and the guiding tube 21 can be secured. While any suitable cooling medium may be circulated through the opening 37 in the jacket 28, it has been found a controlled stream of water will suffice and effect sufficient cooling of the coating 15 to permit the desired smoothing operation that is to be effected by the pressure roller assembly 30 also disposed within the housing 29. For this purpose a pair of fluid connectors 43 and 44 are provided which communicate with opposite portions of the opening 37 and provide for the uniform flow of cooling water through the jacket.

After the coating has been cooled by passage through the jacket 28, the pipe enters the roller assembly 30 which includes three pairs of rollers 45, 46 and 47 disposed in a vertical plane and two pairs of rollers 48 and 49 disposed in a horizontal plane. Each of these rollers are provided with a concave outer surface having a radius equal to the desired finished radius of the coating 15' to be applied to the pipe. The horizontal and vertical rollers are alternated and disposed so that

all portions of the coating are subjected substantially equally to this smoothing pressure.

More specifically, the upper rollers of the pairs 45-47 inclusive are carried in a rectangular bracket member 50 and journaled to the side walls 51 and 52 by transverse axles 53, as shown in Fig. 5. The rectangular member 50 is supported within the outer housing 29 by a pair of lead screws 54 and 55 that threadably engage the wall of the housing 29 and are rotatably secured to the end walls 56 and 57 thereof. The lead screws 54 and 55 are each provided with hand wheels 54' and 55' for adjusting the rollers toward and away from the pipe 15 to effect the desired pressure on the coating 15'. The lower rollers 45 to 47 inclusive are similarly supported within a rectangular bracket member 58 adjustably mounted on the housing 29 by a pair of lead screws 59 and 60. The transverse or horizontal rollers 48 and 49 are supported and mounted in the same manner as the vertically disposed rollers described above and are adjustable by four lead screws of which only two are shown in Fig. 5, namely, lead screws 61 and 62. With this arrangement the horizontal and vertical roller assemblies may be adjusted relative to the pipe 15 to accurately align them with the opening in the jacket 23 and the entrance opening 14 in the bath 10. The rollers function to smooth all imperfections and distortions that may be in the coating after it leaves the cooling apparatus 28 and provides a smooth, homogeneous and uniform coating without entailing the expense of complicated and expensive equipment. At the same time, a firm mechanical bond as well as a chemical bond is secured.

In order to feed the pipe 15 uniformly through the machine, any suitable conveyor means may be employed, such as a link chain 64 and cooperating supporting sprockets 65. With the use of a chain 64, as the translating means, a clamp 66 having a clamping screw 67 is secured about the pipe and coupled with the chain by a link 68 pivotally connected to the clamp 66 and having a hook 69 formed on the outer end thereof for engagement with the chain 64. This translating means provides a simple and effective method of pulling the pipe, since the clamp 66 contacts a substantial area of the pipe and will therefore not materially injure or damage the coating 15'. At the same time, the clamp can be readily and easily loosened and slipped rearwardly of the pipe each time the link member 68 arrives at a point near the end of the conveyor system and little time is lost in repositioning the clamp 66 to feed through another section of the pipe to be coated. In addition, the use of this method of pulling the pipe through the coating apparatus enables the rollers 45 through 49 to be used as smoothing rollers so that longitudinal pressures will not be applied to the coating which may distort it or adversely affect its bond with the pipe.

From the above it is apparent that the illustrated embodiment of the invention provides a simple, effective and relatively high speed method and apparatus for coating or cladding rods, tubing, pipe and other similar articles. Furthermore, by reason of the inherent characteristics of this machine embodying a minimum number of parts, little or no maintenance is required to maintain the equipment in operation and variation in pipe sizes can readily be accomplished merely by interchanging the pipe guides 17, the jacket 28 and the rollers 45-49 to accommodate the new size of the pipe. If desired, this apparatus may also include an annular die 70 positioned between the jacket 28 and the roller assembly 30 for removing a small portion of the cladding 15' and thereby provide more accurate control over the thickness of the cladding.

While only one embodiment of the invention has been shown and described, it is apparent that changes, modifications and alterations may be made without departing from the true scope and spirit thereof.

Having thus described our invention, we claim:

1. In apparatus for cladding pipe, a trough for holding fluid cladding material comprising an elongated receptacle having front and rear walls, said front wall having an entrance opening above the level of said fluid and said rear wall having an exit opening below the level of said fluid and means in said exit opening for aligning the pipe therein and for controlling the thickness of said cladding.

2. In apparatus for cladding pipe, a trough for holding a fluid cladding material comprising an elongated receptacle having front and rear end walls with the depth of the receptacle being shallower at the front wall than at the rear wall, said front wall having an entrance opening above the normal level of the fluid and said rear wall having an exit opening below the normal level of the fluid, and pipe guiding means in said exit opening to control the uniformity and thickness of the cladding applied to the pipe.

3. In apparatus for cladding pipe according to claim 2 wherein said pipe guiding means comprises a tube extending into said fluid in alignment with said entrance opening and having at least three longitudinal ribs of a thickness corresponding to the thickness of the clad to be applied and defining a circular opening of a diameter corresponding to the outside diameter of the pipe to be clad.

4. In apparatus for cladding pipe, a trough for holding a fluid cladding material comprising an elongated receptacle having front and rear end walls with the depth of the receptacle being shallower at the front wall than at the rear wall, said front wall having an entrance opening above the normal level of the fluid and said rear wall having an exit opening below the normal level of the fluid, pipe guiding means in said exit opening to control the uniformity and thickness of the cladding applied to the pipe, and a cylindrical cooling jacket axially aligned with and coupled to said guiding means for hardening the clad after passage through said guiding means.

5. In apparatus according to claim 4 wherein said pipe guiding means comprises a tube extending on one end into said fluid in alignment with said entrance opening and on the other end to a point spaced from said rear wall, said other end of said guide being fixedly connected to and in alignment with said jacket.

6. In apparatus for cladding pipe, a trough for holding a fluid cladding material comprising an elongated receptacle having front and rear end walls with the depth of the receptacle being shallower at the front wall than at the rear wall, said front wall having an entrance opening above the normal level of the fluid and said rear wall having an exit opening below the normal level of the fluid, pipe guiding means in said exit opening to control the uniformity and thickness of the cladding applied to the pipe, a cylindrical cooling jacket axially aligned with

and coupled to said guiding means for hardening the clad after passage through said guiding means, and at least four pressure rollers spaced approximately 90° one from the other and in line with said guide, said rollers forcibly engaging said cladded pipe to smooth the surface of the clad and remove imperfections therefrom.

7. Apparatus for cladding pipe comprising an elongated trough having front and rear walls for holding a fluid cladding material, said front wall having an entrance opening above the normal level of said fluid and said rear wall having an exit opening below the normal level of said fluid, tubular pipe guiding means in said exit opening extending on one end into said trough in alignment with said entrance opening and on the other end to a point spaced from said rear wall, a housing secured to said wall and extending therefrom, a cooling jacket having a central pipe receiving opening secured to said other end of the guiding means, means between said jacket and said housing for aligning said jacket and guiding means with said entrance opening, and a plurality of concave pressure rollers adjustably mounted within said housing and in alignment with said guiding means and cooling jacket for engaging the cladded pipe to smooth the surface thereof.

8. Apparatus according to claim 7 wherein means are provided for forcibly pulling said pipe through said fluid, cooling jacket and pressure rollers.

9. Apparatus according to claim 7 wherein said pressure rollers are arranged in pairs alternately disposed in vertical and horizontal planes.

10. Apparatus for cladding pipe comprising a reservoir for cladding material having front and rear walls, an entrance opening in said front wall above the level of the cladding material and an outlet in said rear wall below the cladding material, said entrance opening and said outlet being in axial alignment with each other, and means in said outlet for aligning the pipe therein.

11. Apparatus for cladding pipe comprising a reservoir for cladding material having front and rear walls, said front wall having a pipe inlet above the level of said cladding material and said rear wall having an outlet therein, means for progressively moving a pipe through said inlet and outlet at an angle with the surface of the cladding material, guide means in said outlet for centering the pipe therein and controlling the thickness of the clad, means for cooling the clad, and pressure rollers for smoothing the surface of the clad and removing imperfections therefrom.
